UNITED STATES PATENT OFFICE.

WILHELM MAUSS, OF JOHANNESBURG, SOUTH AFRICA.

CENTRIFUGAL SEPARATOR AND THE LIKE.

Application filed September 14, 1923. Serial No. 662,702.

To all whom it may concern:

Be it known that I, WILHELM MAUSS, a subject of the King of Great Britain, residing in Johannesburg, Union of South Africa, have invented certain new and useful Improvements in and Relating to Centrifugal Separators and the like, of which the following is a specification.

This invention relates to improvements in continuously rotating continuous separators of the kind described in the specifications of United States Letters Patent Nos. 1,441,732 and 1,419,285.

In Patent No. 1,419,285, a centrifugal separator is described in which the drum consists of a series of axially spaced separating chambers bounded by conical walls and separable by toggle mechanism sliding on the drum shaft structure. The conical walls form peaks between the chambers and on each peak and on the side of the same remote from the feed pipe, a baffle is provided having slots beneath it leading to the next chamber. These baffles hold back any frothy floating matter and the peaks and the overflow lip of the top baffle are at substantially the same radial distance from the axis of the machine.

According to the present invention, the baffles are arranged on the sides of the peaks nearest to the feed inlet. Further, the overflow lip on the top chamber is at a less radial distance from the axis of the machine than the peaks of the lower chambers.

This construction presents advantages in the retaining of solids by the baffles, providing a greater radial depth of liquor and a slower flow over the peaks when the machine is in operation. It also presents advantages when the apparatus is used in the displacement process described in U. S. Patent No. 1,441,732 above referred to in which any liquor in the chambers is washed out by means of a liquid of lighter specific gravity. Owing to the improved arrangement of the baffles the displacing liquid enters practically at the smallest distance possible from the axis of the machine, flows on the inner surface of the liquid under treatment and displaces same to or a little beyond the outer lip of the baffle, so that if the displacing liquid is carefully regulated the dilution of the total separated liquor at the top overflow or discharge point of the machine is practically nil.

A further feature of the invention con-

sists in the method of mounting the drum sections and the baffles. In this method, the top baffle ring and the top drum section are fixed to a cylinder which is slidably mounted on a central driving shaft and operated by means of toggle mechanism. The remaining baffle rings each carry a drum section and are freely slidable on the cylinder, the cylinder being of different diameter for each ring and having a shoulder formed thereon adapted to raise the baffle and drum section when said cylinder is raised. The drum is closed by a fixed bottom section. The shoulders on the cylinder are so spaced and arranged as to raise the baffle rings and drum sections to cause an opening of the drum sections when the cylinder is raised by the toggle mechanism.

The baffles are in the form of solid rings or discs having bosses thereon which form openings between the peaks of the drum sections and the baffles so that no liquor can pass under any circumstances except by flowing over the peripheries of the baffles.

The drum is mounted in a receiver having a discharge outlet for solids and also an outlet for the separated liquor as in the specifications above referred to.

To enable the invention to be fully understood it will now be described by reference to the accompanying drawings, in which:—

Fig. 1 is a sectional elevation of a separator constructed according to the invention, the separator chambers being closed, and

Fig. 2 is a similar view shewing the chambers open.

Fig. 3 is a sectional view of the inner portion of the apparatus, showing the mechanism for opening and closing the chambers.

As shewn the drum comprises the separate rings 1 and fixed bottom ring 2 forming a series of chambers bounded by conical walls. The rings 1 are each mounted on baffle rings 3 slideable on a cylinder 4, the cylinder being slideable on a central driving shaft structure 5, by toggle mechanism 6 operated by a rod 7. The top ring 1^a is of a slightly different shape and is secured to the cylinder 4, a separate baffle 1^b being attached to the cylinder below the ring first mentioned.

The use of the baffle 1^b is optional. The toggle levers 6 are each pivoted at 50 to a guide ring 51 secured to a boss 52 carried by the shaft 5. The lower ends of the toggles are pivoted at 53 to a ring 54 secured to

the bottom of the cylinder, said ring being slidable over a guide ring 55 on the bottom bearing. The shaft 5 is rotated by power applied to the pulley 5^a and rotates the drum 5 and cylinder. If the rod 7 is raised by suitable means the toggles 6 are operated and raise the cylinder from the bottom, the ring 51 being a sliding fit with the cylinder.

When the rod 7 is lowered, the cylinder is 10 also lowered. The cylinder 4 is of a different diameter for each ring 3 and is provided with shoulders 8 arranged one below each ring 3 and so spaced that when the cylinder is raised by the toggle mechanism 6 as above 15 described, the rings 1 and 3 will be raised and the chambers formed by the rings 1 will be opened. When the cylinder is lowered the rings also slide down and close the chambers.

20 The baffle rings 3 are attached to the peaks 9 formed between the chambers and on the sides of the peaks nearest the feed inlet 10 and are in the form of solid rings spaced away from the walls of the chamber by 25 bosses through which the securing bolts 11 pass, passages 12 being thus formed between the chamber wall and the baffle. In the construction illustrated all the chambers are intended to retain the lighter material in 30 the section of the chamber within the radial limits of the baffle rings. The overflow lip 6 on the top chamber is at a less radial distance from the axis of the machine than the other peaks, providing a greater radial 35 depth of liquid and slower flow over the lower peaks.

The drum is mounted in a receiver 14 having a discharge opening 15 for solids at the bottom and an annular passage 16 and 40 discharge outlet 17 for the separated liquor at the top.

The operation of the apparatus is as previously described in the aforesaid U. S. patents to which reference may be had.

45 Fig. 2 shews the apparatus with the separator chambers opened for discharge of solids.

Having thus described the nature of my said invention and the best means I know 50 of carrying the same into practical effect, I claim:—

1. In a centrifugal decanter, a drum composed of sections forming between them V-sectioned settlement chambers separated 55 by peaks and axially separable to discharge solids from said chambers, said drum having an inlet and a liquid overflow remote from said inlet, and baffles arranged on the sides of the peaks nearest to the inlet of the apparatus.

2. In a centrifugal decanter, a drum composed of sections forming between them V-sectioned settlement chambers separated 60 by peaks and axially separable to discharge solids from said chambers, said drum hav-

ing an inlet and a liquid overflow remote from said inlet, baffles arranged on the sides of the peaks nearest to the feed inlet of the apparatus, the top chamber having an overflow lip at a less radial distance from the 70 axis of the machine than the peaks of the lower chambers.

3. In a centrifugal decanter, a drum composed of sections forming between them V-sectioned settlement chambers separated 75 by peaks and axially separable to discharge solids from said chambers, said drum having an inlet and a liquid overflow remote from said inlet, solid ring baffles on the sides of the peaks nearest to the feed inlet of the apparatus and means holding 80 said baffles and peaks apart and forming passages between the peak walls and the baffles.

4. In a centrifugal decanter, a central 85 cylinder, means on which said cylinder is slidable, a drum surrounding said cylinder and composed of sections forming between them V-sectioned settlement chambers separated by peaks and 90 axially separable to discharge solids from said chambers, said drum having an inlet and a liquid overflow remote from the inlet, baffle rings secured in spaced relation to the sides of the peaks nearest to the feed 95 inlet of the apparatus and slidably mounted on said cylinder.

5. In a centrifugal decanter, a central cylinder, a drum surrounding said cylinder and composed of sections forming between them V-sectioned settlement chambers separated by peaks and axially separable to discharge solids from said chambers, said drum having an inlet and a liquid 100 overflow remote from said inlet, the uppermost chamber having an overflow lip at a less radial distance from the axis of said cylinder than the peaks of the lower chambers, baffle rings secured to the sides of the peaks nearest to the feed inlet of the apparatus and slidably mounted on said cylinder, 105 said baffle rings being spaced from the peaks of said chambers with which they are respectively associated.

6. In a centrifugal decanter, a central 110 cylinder, a drum surrounding said cylinder and composed of sections forming between them V-sectioned settlement chambers separated by peaks and axially separable to 115 discharge solids from said chambers, said drum having an inlet and a liquid overflow remote from said inlet, baffle rings secured to the sides of the peaks nearest to the feed inlet of the apparatus and slidably mounted on said cylinder, a top drum section fixed 120 to the cylinder and means on which the cylinder is slidable.

7. In a centrifugal decanter, a central cylinder having a plurality of shoulders on its periphery, a drum surrounding said 125

- cylinder and composed of sections forming between them V-sectioned settlement chambers separated by peaks and axially separable to discharge solids from said chambers, said drum having an inlet and a liquid overflow remote from said inlet, baffle rings secured to the sides of the peaks nearest to the feed inlet of the apparatus and respectively slidably mounted on said cylinder above said shoulders, a top drum section fixed to the cylinder and means on which said cylinder is mounted to slide.
8. In a centrifugal decanter, a central cylinder having a plurality of shoulders on its periphery and being of larger external diameter below each of said shoulders, a drum surrounding said cylinder and composed of sections forming between them V-sectioned settlement chambers separated by peaks, said sections being axially separable to discharge solids from said chambers, said drum having an inlet and a liquid overflow remote from said outlet, a baffle ring secured to the side of each of said peaks which is nearest to the feed inlet of the apparatus, said baffle rings being slidably mounted, respectively on said cylinder above said shoulders, a top drum section fixed to the cylinder, means on which the cylinder is slidable, the top chamber having an overflow lip at a less radial distance from the axis of said cylinder than the peaks of the lower chambers.
9. In a centrifugal decanter, a central cylinder, a drum surrounding said cylinder and composed of sections forming between them V-sectioned settlement chambers separated by peaks, said sections being axially separable to discharge solids from said chamber, said drum having an inlet and a liquid overflow remote from said inlet, the top drum section being fixed to the cylinder, a baffle on the cylinder on the side of the peak of said chamber nearest to the inlet of the apparatus, baffle rings secured to the peaks of the lower chambers on the sides of the latter nearest to the inlet and slidably mounted on the cylinder and means on which the cylinder is slidable.
- In testimony whereof I have signed my name to this specification.

WILHELM MAUSS.
